Primary Examiner — Marianne Pandozzi*Assistant Examiner* — Jae Liang(74) *Attorney, Agent, or Firm* — Cook Alex Ltd.(57) **CLAIM**

The ornamental design for a hydration bottle, as shown and described.

DESCRIPTION

FIG. 1 is a front perspective view of a hydration bottle showing my new design;

FIG. 2 is a top plan view thereof;

FIG. 3 is a bottom plan view thereof;

FIG. 4 is a right side view thereof;

FIG. 5 is a rear view thereof;

FIG. 6 is a left side view thereof; and,

FIG. 7 is a front view thereof.

The broken line showing in the figure drawings are included for the purpose of illustration and form no part of the claimed design.

1 Claim, 3 Drawing Sheets(56)
